UNITED STATES PATENT OFFICE.

THOMAS R. GREENE, OF TEXARKANA, ARKANSAS.

GATE-SUPPORT.

1,243,931.

Specification of Letters Patent. Patented Oct. 23, 1917.

Application filed September 28, 1916. Serial No. 122,732.

To all whom it may concern:

Be it known that I, THOMAS R. GREENE, a citizen of the United States, residing at Texarkana, in the county of Miller and State 5 of Arkansas, have invented certain useful Improvements in Gate-Supports, of which the following is a specification, reference being had therein to the accompanying drawing.

10 This invention has for its object the provision of a gravity controlled means for supporting a gate, barn door or the like in a manner to prevent sagging of the same, and to further relieve the hinges or other supports therefor of undue strain.

In carrying out the invention I further aim to provide a support of the above mentioned character which permits of the closure member which may be either a gate or 20 door being easily opened and closed, and further operating to hold the closure member in either of its respective positions and serving to facilitate the opening of the closure member subsequent to its release from 25 a closed position.

Among the other aims and objects of this invention may be recited the provision of a device of the above character with a view to compactness, and in which the number of 30 parts are few, the construction simple, the cost of production low and the efficiency high.

Other objects as well as the nature, characteristic features and scope of this invention will be more readily apparent from the 35 following description taken in connection with the accompanying drawings and pointed out in the claim forming a part of this specification.

40 In the drawings forming part of this specification like numerals of reference indicate similar parts in the several views and wherein:—

Figure 1 is a side elevation of a gate showing one method of supporting the latter in accordance with my invention.

Fig. 2 is an end view thereof.

Fig. 3 is a fragmentary top plan view.

While the support forming the subject 50 matter of my invention is shown and described in connection with a swingable gate, I desire to have it understood that it is also susceptible for use with barn doors or the like, and its general application is contemplated by the claim.

Referring to the drawings in detail, 10

indicates a gate which may be of any suitable construction and which is supported by hinges 11 upon the post 12 which permits the gate to swing between the respective posts 60 12 and 13. Rising from the upper rail of the gate 10 at appropriate points adjacent the opposite end of the gate are spaced eye bolts 14 and 15 respectively, each of which has swivelly connected thereto through the 65 instrumentality of a staple 16, a pulley 17. An eye bolt 18 is secured to the post 12 an appropriate distance above the upper edge of the gate, and has secured thereto one end of a flexible element 19 such as a 70 chain or the like, and which element extends downwardly as at 20 passing beneath the pulleys 17 in parallelism with the upper edge of the gate. The flexible element passes from the last pulley 17 upwardly in the 75 direction of the upper end of the post 12 and is trained over a pulley 21, which latter is swivelly supported by an eye bolt 22, which depends from a cross arm 23 at the upper extremity of the post 10. Suspended 80 from the opposite terminal of the flexible element 19 is a weight 24 whose function is primarily to prevent sagging of the gate and to relieve the hinges thereof of undue strain. The weight is further adapted to hold the 85 gate normally in its closed position, but when it is properly balanced it will serve equally as well to hold the gate in its opened position.

It is believed that from the foregoing description the nature and advantages of the invention will be readily apparent without requiring a more extended explanation and therefore the same has been omitted; however it is desired to have it understood that 90 such changes in the construction and arrangement of parts may be resorted to when desired as fall within the scope of what is claimed. It might also be added that any one of the different forms of the invention 95 herein shown and described can be easily applied to a gate or door without necessitating any alterations of the latter.

What is claimed is:

The combination with a supporting post, 105 a closure member, means for connecting one end of the member for horizontal swinging movement to the lower portion of the post, a cross bar connected to the upper edge of the post and arranged at right angles to the 110 plane of the member when the member is in a closed position, two pulleys swivelly

connected to the upper edge of the closure member and positioned adjacent the respective ends thereof, another pulley pendently supported from the under surface of the 5 arm adjacent one end thereof, a cable one end of which is rigidly connected to the post adjacent the upper edge thereof, the cable being extended downwardly and operatively trained about the inner and outer pulleys 10 on the closure member and thence extending outwardly and trained about the pendently supported pulley on the cross bar, and a weight carried by the depending portion of

the cable continuing from the pendently supported pulley for co-operating with the 15 cable in exerting parallel and lateral force on the closure member to prevent sagging of the closure member to relieve strain on the connecting means of the closure member, and in addition hold the closure member in 20 either an open or closed position and to facilitate opening of the closure member subsequent to the release thereof.

In testimony whereof I affix my signature.

THOMAS R. GREENE.
